UNITED STATES PATENT OFFICE.

HERBERT C. BEAGARY, OF PHILADELPHIA, PENNSYLVANIA.

DESIGN FOR A DOLL.

61,080.

Specification for Design. Patented June 20, 1922.

Application filed January 14, 1922. Serial No. 195. Term of patent 7 years.

To all whom it may concern:

Be it known that I, HERBERT C. BEAGARY, a citizen of the United States, residing in Philadelphia, county of Philadelphia, and State of Pennsylvania, have invented a new, original, and ornamental Design for a Doll, of which the following is a specification, reference being had to the accompanying drawing, forming a part thereof.

In the drawings, Figures 1 and 2 are respectively front and rear perspective views of a doll showing my new design.

I claim;

The ornamental design for a doll as shown.

HERBERT C. BEAGARY.
